EXTREME PRESSURE LUBRICANT

Bernard H. Shoemaker, Hammond, Ind., assignor
to Standard Oil Company, Chicago, Ill., a cor-
poration of Indiana

No Drawing. Application September 12, 1938,
Serial No. 229,523

11 Claims. (Cl. 252—46)

This invention relates to improvements in lub-
ricants, and in particular, to improvements in
extreme pressure lubricants adapted for use on
bearing surfaces which are subjected to high
pressures and high rubbing velocities during use.

High unit pressures which are encountered
frequently in devices employed for the trans-
mission of power, such as hypoid gears, worm
gears, heavy duty bearings, planetary automatic
shifts and the like, necessitate the use of lubri-
cants having superior load carrying properties.
Lubricants possessing superior load carrying
properties, which make them specially adapted
for use under conditions of high pressure where
the pressures encountered are of such magnitude
that the separation of gear teeth or bearing sur-
faces by an ordinary oil film is not possible, are
known in the art as extreme pressure lubricants.
Extreme pressure lubricants are likewise impor-
tant in cutting and drawing operations where the
oil must withstand the high pressures encoun-
tered under those conditions of use.

It is an object of this invention to provide an
improved extreme pressure lubricant which will
give superior lubrication to bearing surfaces
which are subjected to high pressures and/or
high rubbing velocities.

Another object of this invention is to provide
a lubricant which will prevent gear teeth or bear-
ing failure from scoring or galling caused by the
welding of small areas of the mating surfaces
due to high pressure and high temperature.

I have found that the foregoing objects can be
attained if small amounts, preferably from about
0.01% to about 2%, of thioketopolysulfides, of
the type obtained by reacting an alkali-metal
xanthate with a sulfur chloride, are added to
lubricants, such as oils and greases. These com-
pounds have the general formula $(RXC=S)_2S_n$,
in which R is a radical selected from the group
consisting of alkyl, chloralkyl, aryl and chloraryl
radicals, X is an element selected from the group
consisting of oxygen and sulfur, and n is an in-
teger greater than 2.

These compounds may be prepared by react-
ing an alkali metal xanthate with a sulfur chlo-
ride. For example, the tetrathio derivative may
be prepared by reacting twenty-eight grams of
potassium ethyl xanthate, suspended in hexane,
or any other suitable diluent, with a little less

than the calculated required amount of S_2Cl_2 ,
and refluxing the reactants on a steam bath for
about two hours. The following reaction is be-
lieved to take place:

To obtain the trithio derivatives the alkali metal
xanthate is reacted with SCl_2 .

Because of the presence of the thio-keto group

15 in these compounds I have called them thioketo-
polysulfides, but more specifically I believe them
to be thioformate polysulfides, and while I refer
to them hereinafter as thioformates, I do not wish
to limit the scope of this invention to thioform-
ates, but to the reaction product of an alkali-
metal xanthate and a sulfur chloride.

Specific examples of the type of compounds
which I may use are the following:

Tetrathio diethylthioformate
Tetrathio dibutylthioformate
Tetrathio diamyldithioformate
Tetrathio dilaurylthioformate
Tetrathio dilauryl dithioformate
Tetrathio dichlorbutylthioformate
Tetrathio dichlorlauryldithioformate
Tetrathio diphenylthioformate
Tetrathio dichlorphenyldithioformate
Trithio dipropylthioformate
Trithio dichlorbutylthioformate
Trithio diphenylthioformate
Trithio di-octyldithioformate

40 I have found that small amounts of these com-
pounds added to lubricating oils and greases pro-
vide lubricants which enable the bearing surfaces
to withstand high pressures and high lubricating
velocities without noticeable wear. Similarly,
these compounds may be compounded with draw-
ing and/or cutting lubricants.

45 The load carrying capacity of extreme pres-
sure lubricants may be determined by extreme
pressure testing machines such as the Almen
testing machine described by Wolf and Mourey
in their paper on "Extreme Pressure Lubricants"
given at the 13th annual meeting of the A. P. I.

at Houston, Texas, November 17, 1932. Briefly, it consists of a test pin or journal made of $\frac{1}{4}$ inch diameter drill rod which can be rotated in a $\frac{1}{2}$ inch long split bushing with provisions for loading the bearing thus formed by clamping together the two halves of the split bushing. Provision is also made to measure the torque required to rotate the journal in the loaded bearing.

The standard method of making a test on the Almen machine consists in immersing the test pin and bushings in the lubricant to be tested and then rotating the test pin at 600 R. P. M. The load, which clamps the two halves of the split bushing, is increased at the rate of 2 lbs. added every 10 seconds. A record is made of the torque required to rotate the pin at each load increment and the test is completed either when 30 lbs. have been added to the loading device or when seizure occurs, whichever happens first.

The following example will illustrate the effectiveness of the addition of small amounts of thioketo polysulfides in lubricating oils under extreme pressure conditions. A mineral lubricating oil having a viscosity of about 170 seconds at 130° F. and the same oil with 0.5% of tetrathio diethylthioformate when tested in the Almen testing machine gave the following results:

	Load at which seizure occurred	
	Pounds	Pounds
Control	16	6
Control+0.5% tetrathio diethylthioformate	30	30+

While I have described my invention with a specific embodiment thereof, it is to be understood that the same is merely illustrative of the invention and not a limitation thereof, except insofar as the same is defined in the appended claims, which are to be interpreted as broadly as the prior art will permit.

I claim:

1. An extreme pressure lubricant containing a lubricant and a thioketo polysulfide having the general formula $(RXC=S)_2S_n$ in which R is a radical selected from the group consisting of alkyl, chloralkyl, aryl and chloraryl radicals, X is an element selected from the group consisting of oxygen and sulfur and n is an integer greater than 2, said thioketo polysulfide being used in small but sufficient quantities to impart extreme pressure properties to said lubricant.

2. An extreme pressure lubricant containing a

mineral lubricating oil and from about 0.01% to about 2% of a thioketo polysulfide having the general formula $(RXC=S)_2S_n$ in which R is a radical selected from the group consisting of alkyl, chloralkyl, aryl and chloraryl radicals, X is an element selected from the group consisting of oxygen and sulfur and n is an integer greater than 2.

3. An extreme pressure lubricant containing a mineral lubricating oil and from about 0.01% to about 2% of tetrathio diethylthioformate.

4. An extreme pressure lubricant containing a lubricant and a thioketo polysulfide having the general formula $(RXC=S)_2S_3$ in which R is a radical selected from the group consisting of alkyl, chloralkyl, aryl and chloraryl radicals, and X is an element selected from the group consisting of oxygen and sulfur, said thioketo polysulfide being used in small but sufficient quantity to impart extreme pressure properties to said lubricant.

5. An extreme pressure lubricant containing a lubricant and a thioketo polysulfide having the general formula $(RXC=S)_2S_4$ in which R is a radical selected from the group consisting of alkyl, chloralkyl, aryl and chloraryl radicals, and X is an element selected from the group consisting of oxygen and sulfur, said thioketo polysulfide being used in small but sufficient quantity to impart extreme pressure properties to said lubricant.

6. An extreme pressure lubricant containing a lubricant and a tetrathio alkyl thioformate in small but sufficient quantity to impart extreme pressure properties to said lubricant.

7. A lubricating composition comprising a lubricating oil base stock and at least .01% of a soluble xanthogen sulfide having the general formula:

where R and R' are like or unlike alkyl or aryl radicals, and X is either oxygen or sulfur.

8. A composition of matter comprising an oil and a small amount of organic xanthogen tetrasulfide.

9. A lubricating composition comprising a mineral lubricating oil and at least about 0.01% of a soluble organic xanthogen tetrasulfide.

10. A lubricating composition according to claim 9 in which the tetrasulfide is an alkyl xanthogen tetrasulfide.

11. A lubricating composition according to claim 9 in which the tetrasulfide is ethyl xanthyl tetrasulfide.

BERNARD H. SHOEMAKER.
